HIGH FREQUENCY OSCILLATOR

Alfred H. Turner, Collingswood, N. J., assignor
to Radio Corporation of America, a corpora-
tion of Delaware

Application July 31, 1935, Serial No. 33,955

9 Claims. (Cl. 250—36)

My invention relates to oscillators. Specifically, my invention is an improved high frequency oscillator having substantially constant frequency over a wide range of plate and heater potentials.

One object of my invention is an improved ultra high frequency oscillator.

Another object is an oscillator circuit having substantial constant frequency over a wide range of plate voltage and heater potentials.

Another object is to provide a high frequency oscillator whose voltage output is relatively constant within the tuning frequency range.

A still further object is to combine, in a single oscillator, the characteristics of constant frequency and a constant coupling output circuit.

Other objects will appear from the following specification and claims.

Figure I is a schematic diagram of a conventional oscillator.

Figure II is a diagram of an oscillator employing a tracking condenser,

Figure III is a diagram of an oscillator embodying one form of my invention,

Figure IV is a modification of Figure III,

Figure V is a graph showing the variation in output frequency with changes in plate voltage,

Figure VI is a graph showing the variation in output frequency with changes in heater voltage,

Figure VII is a graph showing the variation of grid and plate current with frequency, and

Figure VIII is a graph showing the variation of frequency with varying plate voltage for different values of grid leak resistance.

The circuit illustrated in Figure I is a vacuum tube oscillator employing a tuned grid circuit and tickler feedback. This circuit arrangement is well known to those skilled in the art. A circuit of this type has objectionable characteristics.

The oscillatory voltages across the tuned circuit will be substantially reduced as the frequency is decreased. If used in a heterodyne receiver, the oscillator will not track with tuned preselector circuits unless special variable condensers are employed. The greatest difficulty is experienced at high frequencies where the frequency cannot be stabilized to any substantial degree. A further undesired variation in oscillator frequency takes place with changing plate and heater potentials.

This latter effect becomes very serious at high frequencies. I am aware of numerous arrangements for overcoming these difficulties. Some of these arrangements are satisfactory at broadcast frequencies but are not applicable at ultra high frequencies of the order of 30 megacycles and up-

ward. Some of the theory of oscillators applicable to low frequencies is far from rigorous at ultra high frequencies. My present invention minimizes and compensates the deleterious effects usually experienced in high frequency oscillator circuits.

In Figure II is illustrated a modified form of oscillator similar to Figure I. In Figure II, a grid inductance 1 is connected through grid condenser 3 to grid 5 of thermionic tube 7. The lower end of the grid inductance is connected to plate inductance 9 which is connected to plate 11. The junction of the grid and plate inductances is coupled through tracking condenser 13 to the cathode 15 which is grounded. A variable tuning capacity 17 is connected from the upper terminal of the grid inductance to the cathode and ground. A grid leak resistance 19 is connected between grid and cathode. The B battery 21 has its negative terminal grounded and its positive terminal connects to the upper end of the plate inductance through the radio frequency choke 23. The B battery may be by-passed by a suitable capacity 25. The cathode 15 is heated by filament 27. Inductances 1 and 9 are preferably 25 mutually coupled.

Although the circuit of Figure II may be adjusted by properly choosing the value of 13 to track with tuned circuits in a superheterodyne receiver or the like, it still has objectionable characteristics at frequencies of the order of 30 megacycles and upward. In Figure V the curve A represents the effect of varying the plate voltage on the frequency output of the circuit of Figure II. It is customary to supply the plate voltage from a rectified filtered source of power derived from a commercial sixty cycle 110 volt supply. Such sources have been known to vary as much as twenty-five percent in the case of poorly regulated lines and as much as thirty percent in different sections of the country. Such variation would have a serious effect on the oscillator of a superheterodyne.

A similar variation in a tuned grid circuit oscillator, although in the opposite direction, is found in Figure VI, curve C. In this curve the effect of varying heater voltage in terms of frequency change is shown. The curves E, and F, of Figure VII, illustrate the variation of grid and plate currents with frequency in the case of a tuned grid circuit oscillator. Since the effective output of oscillatory current is proportional to the grid current, the large variation of output in the oscillatory current of a tuned grid circuit 55

oscillator is objectionable from a constant current standpoint.

The foregoing examples of variation in the frequency output of a tuned grid circuit oscillator apply especially when the frequency range is from about 30 megacycles and upward. Although the curves are based on observations of the characteristic of an RCA type 955—Acorn type tube, it should be understood that similar frequency variations are present in other types of tubes connected to similar circuits.

Many variable factors make it difficult to mathematically treat the tubes and associate circuits to derive equations which explain the variations. Among the important variable factors at ultra high frequencies is the recently recognized variation caused by changes of space charge and electron velocity within the tube with changing plate and filament potentials. This variation appears to alter the effective interelectrode capacities within the tube. Some variable factors may be minimized and others compensated.

One important effect at high frequencies, is the variation in the effective grid, cathode and/or grid-plate capacity with variations in plate circuit impedance. The increase in frequency is primarily due to a decrease in the effective grid to cathode capacity. If the oscillatory circuit is inserted in the plate circuit, variations in effective capacity between grid and cathode will have little effect, because the tuned plate circuit primarily determines the frequency.

Figure III is a diagram of a tuned plate circuit oscillator. An inductance 31 is connected through grid condenser 33 to grid 35 of tube 37. The lower end of 31 is connected to inductance 39. The lower terminal of 39 is connected to plate 41. The junction of 31 and 39 is connected through tracking capacity 43 to cathode 45 which is grounded. A variable tuning capacity 47 is connected between ground and the lower terminal of inductance 39. A grid leak 49 is connected between grid and ground. The negative terminal of B battery 51 is grounded. The positive terminal of the battery is connected through the radio frequency choke 53 to the junction of 31 and 39. A by-pass condenser 55 may be shunted across the B battery. A heater 57 of the conventional type heats the cathode 45. A comparison of Figures II and III indicates that the essential difference is the tuning of the grid circuit of the former and the tuning of the plate circuit of the latter.

While a comparison of diagrams indicates a similarity, a comparison of graphs, Figures V, VI and VII, discloses substantial differences. In Figure V the curve B shows a substantially constant frequency with varying plate voltage. A comparison of A and B indicates a very great improvement. In like manner curve D of Figure VI shows that from 7 volts to 5.3 volts of heater potential the frequency is practically unchanged. Curve C shows a substantial variation of frequency with decreasing heater voltages beginning at 6.3 volts. The curves shown in Figure VII indicate that the radio frequency output which accompanies curve G is more constant than that indicated by curve E. Because of the shape of curve G the variations in output with frequency may be compensated by various types of compound coupling linking the oscillator output and the work circuit. Such compound coupling keeps the applied voltage constant with changes in oscillator frequency.

While the principal gain in frequency stability is illustrated by curves B and D of Figures V and

VI, respectively, is due to plate circuit tuning in place of grid circuit tuning, the results are not entirely due to this change. Part of the stability indicated by curve B is due to compensating means I employ. The circuits of the several figures, when employing a grid leak resistance of the order of one hundred thousand ohms, show an increase in frequency with increasing plate potentials. I have observed the effect of lowering the grid leak resistance is to cause a change in the frequency characteristic with changing plate voltage which over a portion of the range is opposite to the usual frequency increasing tendency. The result of such observation is found in Figure VIII. The curves J and K with 100,000 ohm grid leak resistances show a rising frequency characteristic with increased plate voltages. The curves L and M show a rising frequency characteristic at low voltages and a reversal of slope for higher voltages. By a suitable choice of operating voltage and grid resistance, the ordinary rising frequency characteristic with increasing plate voltage, may be compensated. In curves L and M a value of grid leak resistance is employed which approaches the optimum value for a constant frequency output with increasing plate voltages.

Figure IV is a diagram showing a modification of Figure III. The grid circuit inductance 61 is connected through grid condenser 63 and grid leak 65 to grid 67 of tube 69. The lower terminal of 61 is connected to cathode 71 and ground. The plate circuit inductance 73 is connected between the plate 75 and the positive terminal of B battery 77. The B battery has its negative terminal grounded. The variable tuning capacity 81 is connected between ground and the junction of inductance 73 and plate 75. The tracking condenser 83 is connected between the lower terminal of 61 and the upper terminal of 73. The condenser 83 also acts as a by-pass for battery 77. The essential difference between the circuits shown in Figures III and IV is that in the latter the grid leak resistance is serially connected to the grid circuit and has a smaller loading effect in this position. The lesser loading effect of the grid resistance is an advantage in a number of circuit arrangements.

Although my invention may be applied to any oscillator, it is primarily designed for a high frequency oscillator and is particularly suited to a superheterodyne receiver. The tracking condensers 13 and 43 of Figures II and III are suitable for aligning the oscillator with respect to the preselector circuits. The combination of the mutual inductive coupling and the capacity of these condensers increases the coupling between the grid and plate circuits at the lower frequencies, and tends to keep the output oscillations constant in amplitude throughout the frequency range. In many cases, I find the tracking condenser capacity must be large with respect to the tuning capacity. This large ratio is not the optimum for impressing a constant voltage on the work circuit. In such cases, I employ, a compound coupling between the oscillator and first detector or work circuit. The compound coupling keeps the impressed voltage on the first detector substantially constant as the oscillator is tuned throughout the frequency range.

By way of example I have employed the following constants in the circuit of Figure III: Grid circuit inductance two turns number 19 enameled copper wire on 1¹⁵'' diameter form. Plate circuit inductance four turns number 19 enameled copper wire on 1¹⁵'' diameter form. 75

Both the grid and plate circuit inductances are a continuous winding of six turns spaced about one-eighth of an inch on a common form. The tuning condenser is variable from five micro-
5 microfarads to twenty micromicrofarads. The common condenser is eight hundred micromicrofarads. The grid condenser is thirty-five micromicrofarads and the grid leak about 10,000 ohms. An Acorn tube RCA 955, is preferred. A plate
10 voltage of 135 volts may be used. The rated heater voltage of 6.3 volts is employed.

The circuits described cover arrangements of my invention which give substantially constant high frequency outputs with varying plate and heater potentials. The amplitude of the output current is substantially constant over the tuning range, and the voltage applied to a work circuit may be made uniform by employing the above mentioned compound coupling. The circuit dia-
20 grams, curves, and constants are given merely by way of example. I do not intend to limit my invention to the precise arrangements shown because other obvious arrangements within the scope of my invention will occur to those skilled
25 in the art.

I claim:

1. In an ultra high frequency oscillator, a thermionic tube having grid, cathode, and plate electrodes with relatively low interelectrode ca-
30 pacities; means for moving electrons from cathode to plate whereby the effective interelectrode capacities are varied; means for tuning the plate circuit throughout a range of ultra high frequencies; an inductance serially included in the grid circuit; means connected in said grid circuit having an impedance which establishes an increasing, then a decreasing frequency characteristic in said oscillator with increasing plate voltage; and means mutually coupling said grid and plate
35 circuit, whereby the effect of said moving electrons on the frequency characteristic of said oscillator is substantially reduced.

2. In an ultra high frequency oscillator, a thermionic tube having grid, cathode, and plate electrodes with relatively low interelectrode ca-
45 pacities; means for moving electrons from cathode to plate whereby the interelectrode capacities are apparently varied; means for tuning the plate circuit throughout a range of ultra
50 high frequencies; an inductance, and grid condenser serially connected between grid and cathode; means connected in said grid circuit having an impedance which establishes an increasing then a decreasing frequency characteris-
55 tic in said oscillator with increasing plate voltage; and means mutually coupling said grid and plate circuits, whereby the effect of said moving electrons on the frequency characteristic of said oscillator is substantially reduced.

60 3. In an ultra high frequency oscillator, a thermionic tube having grid, cathode, and plate electrodes with relatively low interelectrode ca-
65 pacities; means for moving electrons from cathode to plate whereby the effective interelectrode ca-
70 pacities are varied; means for tuning the plate circuit throughout a range of ultra high frequencies; an inductance, and grid condenser serially connected between grid and cathode; means mutually coupling said grid and plate
75 circuits, whereby the effect of the apparent changes in interelectrode capacities on the frequency of characteristic is minimized; and a grid leak resistance connected between grid and cathode having a value which gives said oscillator a frequency characteristic which increases

then decreases with increasing plate voltage for compensating the frequency variation caused by the apparent change in interelectrode capacity.

4. In an ultra high frequency oscillator, a thermionic tube having grid, cathode, and plate elec-
5 trodes with relatively low interelectrode capac-
6 ities; means for moving electrons from said cath-
7 ode to plate whereby the effective interelectrode capac-
8 ities are varied by said moving electrons; means for tuning the plate circuit throughout a 10 range of frequencies; an inductance and grid condenser serially connected between grid and cathode; a grid resistance effectively connected between grid and cathode and having an ohmic resistance which establishes a frequency char-
15 acteristic which increases then decreases with increasing plate voltage; and means mutually coupling said grid and plate circuits, whereby the effect of said moving electrons on the interelectrode capacities is minimized as to frequency 20 changes in the oscillator.

5. In a device of the character of claim 1, a fixed capacity common to the grid and plate cir-
25 cuits.

6. In a device of the character of claim 1, a fixed capacity serially included in the tuned plate circuit and common to the grid and plate
25 circuits.

7. The method of generating ultra high fre-
30 quency currents of constant frequency in a ther-
mionic tube having control grid, cathode, and plate electrodes; a resonant output circuit; a grid circuit coupled to said output circuit by means of mutual capacitance and mutual in-
35 ductance; and a source of power subject to vari-
ations whereby the movement of electrons in said tube is affected, which comprises generating a potential difference across said resonant out-
40 put circuit, inducing in said grid circuit from said output circuit by means of said mutual ca-
45 pacitance and said mutual inductance a voltage in proper phase to sustain said ultra high fre-
50 quency currents, and limiting the impedance of said grid circuit to a value which establishes a frequency characteristic in said oscillator which increases then decreases with increasing plate voltage and is substantially uninfluenced by apparent capacity changes caused by said move-
55 ment of electrons, whereby constant ultra high frequency oscillations are maintained regardless of the variations in said power source.

8. The method of generating constant ultra high frequency oscillations in a thermionic tube having input and output circuits and avoiding the effect of apparent capacity changes in said tube on said frequency which comprises resonat-
60 ing the output circuit of said tube to the desired frequency, generating voltages across said out-
65 put circuit, feeding from said output circuit volt-
ages to said input circuit having capacitive and inductive components to sustain said resonant output voltages, and substantially limiting the effects of said apparent capacity changes by lim-
70 iting the impedance of said input circuit to a value which will have an increasing and decreasing effect on frequency over a range of plate potentials whereby a constant ultra high frequency oscillation is generated regardless of said apparent capacity changes.

9. The method of generating constant ultra high frequency oscillations in a thermionic tube having input and output circuits coupled by mutual inductance and mutual capacity, and avoiding frequency change caused by variations in the power supplied to said tube and changes in ca-
75

5 pacity due to resultant electron movement which comprises resonating the output circuit of said tube, generating voltages in said output circuit by feeding back voltages through said mutual coupling to said input circuit, amplifying input voltages in said output circuit, and adjusting the impedance of said input circuit to a value

which establishes an increasing and decreasing frequency characteristic in said oscillator with increasing plate voltage and which reflects substantially no reactive component on said resonant output circuit regardless of said power and 5 capacity variations.

ALFRED H. TURNER.
